UNITED STATES PATENT OFFICE.

WILLIAM H. FLURER, OF UNIONTOWN, KANSAS.

HARNESS-SADDLE.

SPECIFICATION forming part of Letters Patent No. 315,757, dated April 14, 1885.

Application filed March 15, 1884. (No model.)

To all whom it may concern:

Be it known that I, WILLIAM H. FLURER, a citizen of the United States of America, residing at Uniontown, in the county of Bourbon and State of Kansas, have invented certain new and useful Improvements in Harness-Saddles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to certain new and useful improvements in harness-saddles, and it has for its object to provide an improved saddle with rigid pads, thereby doing away with the stuffing of the same; and my invention 20 consists, more especially, in the construction and combination of the parts, as will be hereinafter set forth, and pointed out in the claim.

25 In the drawings, Figure 1 is a longitudinal section, and Fig. 2 a transverse section taken through the line *x x* of Fig. 1.

30 A represents the lower portion of the pad, which is of the shape of the ordinary pad, and is constructed of metal, the same being hollow and concave in cross-section, with straight upper edges, *a a*, which at their parallel portions or sides are slightly flared, so as to engage with the downwardly and inwardly projecting flanges *b b* upon the plate *B*, so that when the parts are slipped upon each other 35 they will be retained in position.

35 The covering-plate *B* of the pad is provided with openings *b' b'*, and at suitable points beneath these openings are placed nuts *c c*, by means of which the turrets and fastening-screws are attached to the same. The upper ends of the plates *B* are curved, as shown in Fig. 1, and have extensions at their inner ends by means of which they are united to each other 45 by a flexible connection or leather hinge, *C*, which is secured thereto by means of rivets *c c*, which pass through the end extensions of the plates *B*. This flexible joint will allow the two pads sufficient play, so that they will

properly adjust themselves to the back of the 50 horse. The pads *A A* are covered by pieces of leather *D D*, which are stretched thereon, and secured thereto by threads or stitches *c' c'*, which cross the plate *B* and draw the edges of the leather over the plate at three of its 55 sides. Immediately under the hinge a covering-piece, *E*, is secured, which will form a soft bearing at this portion. The usual cover and straps are held upon the pad by the turrets and screws, which pass through perforations in the same, and are attached to the nuts under the plate *B*. It will be readily seen that by this construction I provide a saddle-pad which is light and cool, and which will fit snugly upon the back of the horse, and 60 which cannot lose its shape or become flattened, and the parts may be readily separated for repairs.

I am aware that previous to my invention it has been proposed to employ metal padding- 70 forms in a harness-saddle, and that blocks of wood or like material have been embraced by metal secured at its free edges to loop plates by flange-joints thereof. My invention will, however, be readily distinguished from such 75 constructions, in that the inner ends of the forms are extended to permit the ready attachment of the flexible connecting means, which, in combination with the metal forms, presents another improved feature of my in- 80 vention.

Having thus described my invention, what I claim as new, and desire to secure by Letters Patent, is—

The combination, in a harness-saddle, of the 85 hollow metallic forms *A*, each of which has an integral extension at its inner end, a flexible strap connecting the two extensions, top plates resting on said forms and having flanges embracing the free edges of the same, and suitable coverings and finishings, substantially as set forth.

In testimony whereof I affix my signature in presence of two witnesses.

WILLIAM H. FLURER.
